UNITED STATES PATENT OFFICE.

HENRY A. WEBSTER, OF MILFORD, MASSACHUSETTS, ASSIGNOR, BY DIRECT AND
MESNE ASSIGNMENTS, TO GEORGE E. W. LUEHRMAN, OF ST. LOUIS, MISSOURI.

WRINGER.

Application filed July 29, 1920. Serial No. 399,703.

To all whom it may concern:

Be it known that I, HENRY A. WEBSTER, a citizen of the United States, residing at Milford, Worcester County, Massachusetts, 5 have invented a new and useful Wringer, of which the following is a specification.

This invention relates to wringers, and has special reference to a mechanism for quickly releasing the pressure devices of 10 the wringer rolls, whereby the pressure devices may be quickly released whenever desired, as in case of an emergency.

An object of the invention is to provide a wringer with equipment cooperating with 15 the pressure devices for the wringer rolls, whereby the pressure may be quickly released in a more convenient manner from either side of the wringer than is possible in wringers of ordinary construction.

20 Other objects of the invention will appear from the following description in which reference is made to the drawing showing a preferred embodiment of the invention, and in which—

25 Fig. 1 is a plan view of a wringer equipped with my present invention.

Fig. 2 is a side elevation thereof with parts of the wringer frame members in section, and with the wringer rolls pressed together.

30 Fig. 3 is a similar elevation showing the pressure devices released and in position in which they do not press the rolls together.

As shown, my invention is embodied in a 35 wringer comprising a frame composed of a vertical member 1 and a cooperating vertical member 2, said vertical members being joined by connections 3. The lower wringer roll 4 is supported on and may be 40 driven by power applied to a shaft 5 at one end thereof. The opposite end of the shaft 5 is equipped with a pinion 6 meshing with and driving a pinion 7 which is secured to the shaft 8 of the upper roll 9 45 of the wringer. The shaft 8 of the upper roll is journaled for rotation in vertically movable blocks 10 supported in the vertical end members 1 and 2 of the vertical frame. The roll 9 is pressed to a position of co- 50 operating relationship with the roll 4 by an appropriately shaped leaf spring 11 held in position by the vertical end members 1

and 2 of the wringer frame and acting against the upper ends of the bearing blocks 10. The arcuate central portion of the 55 spring 11 is engaged by a pressure bar 12 whose ends are guided for movement by the frame members 1 and 2. By forcing the pressure bar 12 downwardly the spring 11 may be tensioned so to press the roll 9 toward the roll 4, but permitting vertical movement of the roll 9 against the resistance of the spring 11 as required when the wringer is in use and cloth is being passed between the rolls. 65

A bracket 13 is in connection with the upper end of the vertical frame member 1 and has a transverse shoulder 14 under which one end of a cross bar 15 is engaged. The upper end of the vertical frame member 2 is provided with a bracket 16 having a recess 17 arranged to receive one end of a sliding bar 18 which is in connection with the cross bar 15. A slot 19 is formed in the sliding bar 18 through which the stem of 70 a set screw 20 passes, said sliding bar being provided with an additional slot 21 receiving a screw 22 by which said bar 18 is held in position upon the cross bar 15. This construction permits movement of the sliding bar 18 to and from latched connection with the bracket 16. When the sliding bar 18 is in latched connection with the bracket 16 the set screw 20 at one end of the bar 15 and the set screw 23 at the opposite end 75 of said bar may be adjusted to press the pressure bar 12 downwardly as required to tension the spring 11 and presses the roll 9 toward the roll 4. By proper manipulation and adjustment of the set screws 20 and 23 any desired degree of tension may be placed in the spring 11. 85

A push plate or link 24 has one end pivoted at 25 to the sliding bar 18 and has its opposite end pivoted at 26 to one end of a link or push plate 27. The opposite end of the link or plate 27 is connected to the cross bar 15 by a pivot 28 so that by adjusting said plates 24 and 27 in straight or alined position, as shown in Fig. 1, the sliding plate 18 will be held in latched connection with the bracket 16. By breaking the toggle formed by said plates 24 and 27 the sliding plate 18 will be released from its 95 100

latched engagement with the bracket 16 permitting the roll 9 to rise. In order that the toggle may be conveniently broken from either side of the wringer the sliding plate 24 is formed with a handle 29 and, similarly, the plate 27 is formed with a handle 30. The handle 29 may be used to brake the toggle in one direction in an obvious manner, and the handle 30 may be used to break the toggle in an opposite direction.

The cross bar 15 is formed with a recess 31 in which a coil spring 32 is mounted. The spring 32 is of the expansion type and has one end bearing against one of the end walls of the recess 31 and the opposite end bearing against a depending projection 33 on the sliding bar 18 and acts normally to press the bar 18 outwardly beyond the end of the cross bar 15 into latched engagement with the bracket 16.

The toggle action of the plates 24 and 27 results from the fact that the pivot 28 is stationary so that when the toggle is broken the bar 18 will be unlatched or disengaged from the bracket 16; and when the toggle is straightened the sliding bar 18 will be moved outwardly into latched engagement with said bracket.

I am aware that the specific construction and arrangement may be varied without departing from the principle and nature of the invention.

I do not restrict myself to unessential features, but what I claim and desire to secure by Letters Patent, is:—

1. In a wringer comprising the combination of a frame, a lower stationary and an upper movable roller mounted therein, a spring exerting pressure on the upper roller, a cross-bar mounted in said frame and adapted to receive the pressure of said spring, a bar slidably mounted on the top of said cross-bar and adapted to engage under a keeper on the frame at its free end, and a pair of push plates having operating surfaces disposed on opposite sides of said wringer frame, and being pivotally connected, one of said push plates being connected at its inner end to said cross-bar and the other at its inner end to the end of said slidably mounted bar, whereby when the free end of either of said push plates is pressed inward, said bar will be drawn inward and release its free end from engagement with said keeper and thus release one end of said cross-bar and relieve the pressure of the spring on said upper roller.

2. A wringer comprising, in combination with the upper movable roller of the wringer, means including a cross-bar for holding said upper roller under pressure in yielding contact with a lower stationary roller, a rigid bracket engaged by one end of said cross-bar, a latch holding said cross-bar at the opposite end, a push plate opera-

tively connected with said cross-bar and latch for horizontal movement, a spring tending normally to press said latch outward and to hold the push plate in operative position, said push plate being adapted, when pushed inward, to release the latch and thereby free one end of the cross-bar to release the pressure on said upper roller, leaving the other end of said cross-bar in engagement with said rigid bracket.

3. A wringer, comprising a frame, a lower roll mounted in the frame, movable bearing blocks mounted in the frame, an upper roll controlled by said blocks, a spring pressing upon said blocks to hold the upper roll in cooperative relationship with the lower roll, a cross bar mounted in the frame, a device between said bar and said spring for pressing upon said spring, a bracket in connection with said frame, a sliding latch bar carried by said cross-bar for engagement with said bracket, and a pair of pivotally connected push plates, one of which is pivoted to said cross-bar and the other of which is pivoted to said latch bar, whereby when the end of either of said plates is moved inwardly, said latch bar will be moved from engagement with said bracket and thus release one end of said cross-bar and relieve the pressure upon said upper roll.

4. A wringer comprising, in combination with the upper movable roller of the wringer, means including a rigid cross-bar extending from end to end of the wringer, for holding the upper roller under pressure in yielding contact with the lower stationary roller, a standard carrying a keeper, a latch movably mounted on the cross-bar for engaging the keeper for holding the cross-bar down at one end, and a pair of push plates projecting out respectively beyond the side faces of the cross-bar, supported on the cross-bar so as to move in a substantially horizontal plane toward the cross-bar, said push plates having a connection with the latch for sliding the latch to release the same when either push plate is moved toward the cross-bar.

5. A wringer, comprising in combination, a spring-pressed upper roller, a rigid cross-bar receiving the spring pressure, a frame, a latch detachably holding one end of the cross-bar, and an actuating device projecting in a substantially horizontal direction beyond both of the side faces of the cross-bar and movably mounted on the cross-bar so that it can be operated by one's hand when held on either side of the cross-bar by a substantially horizontal movement toward the bar to move the latch and release the same, and thereby relieve the pressure on said upper roller.

6. In a wringer, the combination of a spring-pressed upper roller, a pair of standards, a rigid cross-bar disposed between said standards and receiving the spring pressure,

a latch mounted to slide on the said cross-bar for engaging one of the standards to hold the cross-bar down, a pair of push-plates projecting respectively on opposite sides of the bar, one of the push-plates being attached to the bar and the other to the latch, means for connecting said push-plates

to enable the actuation of either push-plate to actuate the latch, said bar having a recess therein, and a spring mounted within the recess tending to hold the latch in its extended latching position.

H. A. WEBSTER.

Certificate of Correction.

It is hereby certified that the name of the assignee in Letters Patent No. 1,439,655, granted December 19, 1922, upon the application of Henry A. Webster, of Milford, Massachusetts, for an improvement in "Wringers," was erroneously written and printed as "George E. W. Luehrman," whereas said name should have been written and printed as *George E. W. Luehrmann*, as shown by the records of assignments in this office; and that the said Letters Patent should be read with this correction therein that the same may conform to the record of the case in the Patent Office.

Signed and sealed this 23d day of January, A. D., 1923.

[SEAL.]

KARL FENNING,
Acting Commissioner of Patents.
